UNITED STATES PATENT OFFICE

1,975,922

OIL BURNER

William S. Caswell, Lynn, Mass.

Application April 18, 1934, Serial No. 721,190

1 Claim. (Cl. 158—89)

This invention relates to oil burners and it has for its object to provide a novel attachment for an oil burner by which the heating capacity of the burner is improved.

5 Another object of the invention is to provide a novel device of this type which can be readily applied to a burner which is in use and without making any changes or alterations in the burner.

My improvements are in the nature of a flame-spreading attachment to be applied to the top of 10 an oil burner of the type having two annular combustion chambers and it is formed with a perforated cylindrical member adapted to rest on the top of the burner and an annular perforated flame-spreading member secured to the 15 circular member but spaced therefrom and situated above the upper ends of the combination chambers.

The annular flame which issues from the outer 20 combustion chamber is spread outwardly by the flame-spreading member and passes around the periphery of said member while the annular flame issuing from the inner combustion chamber passes up between the flame-spreading member 25 and the cylindrical member, the two flames joining above the flame-spreading member.

The perforated cylindrical member provides for delivering added air to the inner flame and thereby improving combustion.

30 In order to give an understanding of the invention I have illustrated in the drawing a selected embodiment thereof which will now be described after which the novel features will be pointed out in the appended claim.

35 Fig. 1 is a sectional view through an oil burner having my improvements applied thereto;

Fig. 2 is a top plan view of the flame-spreading attachment;

Fig. 3 is a perspective view thereof.

40 In the drawing 1 indicates generally an oil burner of the type having two concentric combustion chambers. This oil burner is formed with the base member 2 which is illustrated as provided with two annular channels or fuel troughs 3, 4 into which the oil or the oil vapor is fed. This base 2 supports a plurality of perforated cylinders 5, 6, 7, 8. The two outer cylinders 5 and 6 form between them an outer annular combustion chamber 9 which communicates with 45 the outer fuel trough or groove 3, and the inner perforated cylindrical walls 7 and 8 form between them an inner annular combustion chamber 10 which communicates at its lower end with the inner annular fuel trough 4.

55 The base 2 is shown as having openings or

passages 11 therethrough through which air may be admitted to the space 12 between the combustion chambers, such air passing into the combustion chambers through the perforations in the cylindrical walls 6 and 7. The base is also 60 provided with a central opening 13 through which air is admitted to the central air chamber 14 within the inner cylindrical wall 8, the air in said chamber passing into the combustion chamber 10 through the cylindrical wall 8.

65 15 indicates a cap plate which closes the upper end of the central air chamber 14 and 16 is a ring member which closes the upper end of the air chamber 12.

The parts thus far described are such as are 70 usually found in oil burners of this type and constitute no part of my present invention, which relates to the attachment shown in Figs. 2 and 3, that is designed to be applied to any oil burner of 75 this type and which operates to increase the heating capacity of the burner. This attachment comprises a cylindrical perforated wall 17 which is adapted to rest on the cap plate 15, and an annular flame-spreading member 18, also preferably of perforated material which is secured to and 80 carried by the cylindrical member 17 but is spaced therefrom so that an annular space 19 is provided between the inner edge 20 of the member 18 and the cylindrical member 17.

85 The member 18 may be secured to the cylindrical member 17 in any approved way. As herein shown I have provided a plurality of brackets 21 which are angle shape and one leg of each of which is welded or otherwise secured to the cylindrical wall 17 and the other leg of each of which 90 is welded or otherwise secured to the flame-spreading member 18.

The member 18 is shown as being deformed around its periphery to produce the rib 22 on its under face, this construction providing the upwardly-curved surface 23 at the periphery of said member 18. Said member may conveniently be provided with a bale 24 which has its end secured to the cylindrical member 17 and by which the 95 device can be manipulated.

100 The flame-spreading member 18 is shown as attached to the cylindrical member 17 at a distance above the lower end thereof so that when the device is in place on the burner with the cylindrical member 17 resting upon the cap plate 15 the 105 flame-spreading member 18 will be spaced a proper distance above the upper ends of the combustion chambers 9 and 10.

The annular space 19 between the inner edge 110 of the flame-spreading member 18 and the cylind-

drical member 17 will be situated above the upper end of the inner combustion chamber 10 and the peripheral edge of the flame-spreading member projects slightly beyond the outer combustion chamber 9.

When the burner is in operation the circular flame which issues from the upper end of the inner combustion chamber 10 will pass up through the annular space 19 as shown by the arrows *a*, 10 and the circular flame issuing from the outer combustion chamber 9 will be deflected outwardly by the member 18 and will spread around the peripheral edge thereof as shown by the arrows *b*. These two flames draw together above the 15 member 18 and produce a relatively wide but annular flame which has superior heating characteristics.

The perforations in the cylindrical member allows air to pass through it thereby furnishing 20 desirable oxygen for continuing the combustion of the flame issuing from the inner combustion chamber 10 and the flame issuing from the outer combustion chamber 9 receives added oxygen from the air as it is passing around the flame-spreading element 18.

70

75

The use of my improvement increases the efficiency of the burner by promoting better combustion.

The device can be inexpensively manufactured and can be readily applied to any burner of the 80 type shown having two concentric combustion chambers.

I claim:

An oil burner having two concentric burner chambers, a flame-spreading attachment provided with a cylindrical perforated member supported on the oil burner within the outline of the inner combustion chamber and a perforated annular flame-spreading member secured to the cylindrical member but spaced therefrom, the annular space between said flame-spreading member and cylindrical member being situated over the inner combustion chamber, whereby the flame issuing from said inner combustion chamber passes up through said space while the flame from the outer combustion chamber passes around the periphery of said member. 90 95
